UNITED STATES PATENT OFFICE.

JAMES MILTON WAUGH, OF CHICAGO, ILLINOIS.

DRAFT-RIGGING.

1,075,741.

Specification of Letters Patent.

Patented Oct. 14, 1913.

Application filed October 10, 1908. Serial No. 457,050.

To all whom it may concern:

Be it known that I, JAMES MILTON WAUGH, a citizen of the United States, and a resident of the city of Chicago, in the county of Cook and State of Illinois, have invented certain new and useful Improvements in Draft-Riggings; and I do hereby declare that the following is a full, clear, and exact description of the same, reference being had 10 to the accompanying drawings, and to the letters of reference marked thereon, which form a part of this specification.

Many of the railways at the present time are equipped with friction draft rigging of 15 various types, wherein co-acting wedge blocks are secured within a casing together with springs in various forms and these wedge blocks by frictional engagement, were supposed to absorb buffing stress. As a matter of fact, years of experience with such equipments have demonstrated that the faces of the wedge blocks are in constant movement relatively each other when a train is under motion, such movement being due to the 20 varying stress due in part to the inequalities of the road and variations in grade so that during the entire operation the faces of the wedge blocks are ground together, soon producing such wear as to cause considerable 25 slack to be present, of course, very materially decreasing the efficiency of the draft gear so far as absorbing stresses is concerned and in very many instances, rendering the draft gears of this type practically worthless. In consequence, roads previously 30 equipped with such devices are abandoning the same to a greater or less extent and it has become an important problem how best to effect a change from draft riggings such 35 as described to another type, with the least possible expense for renewals and labor.

The object of my invention is to insert with the least possible change in the existing equipment and the least possible expense 40 for material and labor, a draft rigging of 45 the type set forth in my prior patents for "draw bar draft rigging for car couplings", No. 690,683, dated Jan. 7, 1902; "draft rigging for railway cars", No. 690,684, dated 50 Jan. 7, 1902; "draft rigging for railway cars", No. 705,172, dated July 22, 1902; "draft rigging for railway cars", No. 731,725, dated June 23, 1903; "draft rigging for railway cars", No. 818,066, dated April 55 17, 1906, whereby although an ideal friction rigging, practically no wearing effect can

occur, and furthermore to afford such frictionally controlled resiliency as to insure the maximum absorption of all the stresses whether buffing or pulling.

It is finally an object of the invention to afford an exceedingly cheap, simple and durable construction for the purpose specified adapted to be inserted in lieu of such draft gear before described without the aid of 60 skilled labor.

The invention consists in the matters hereinafter described and more fully pointed out and defined in the appended claims.

In the drawings: Figure 1 is a fragmentary, central vertical section of a car frame embodying my invention and showing the tail strap for the draft gears in section and likewise the casing and springs therein. Fig. 2 is a fragmentary horizontal section 70 showing the center sills, the tail strap and casing and springs. Fig. 3 is a section on line 3—3 of Fig. 1. Fig. 4 is a perspective view of the abutment block. Fig. 5 is a side elevation of the spring casing 75 embodying my invention.

As shown in the drawings: A, indicates the center sills, and a , the end sill. Said center sills, as shown in Fig. 3, are pressed or rolled Z bars, having the top flanges directed inwardly and the lower flanges a' , directed outwardly, and connected below the draft gear by pressed or rolled sheet steel filler affording side ledges a^2 , and a depressed bottom ledge or floor a^3 , affording 80 together with the center sills a compartment for the draft gear. Rigidly bolted and riveted on the inner side of each center sill near the outer end thereof, are the stationary abutments B, and at a distance therefrom 85 and inwardly equal to the length of the desired draft rigging are the inner abutment blocks B'. These, as shown, comprise inward right angle shoulders against which the follower blocks b — b' abut in practically 90 any type of draft rigging and suitably supported and extending beneath the end sill is the draw-bar C, to which is connected the tail strap C', usually of wrought steel and which is forged or shaped to afford a U 95 shaped strap, the ends c , of which extend one above and the other below the tail of the draw bar, and are riveted or bolted thereto, as shown in Figs. 1 and 2. The upper side of said tail strap C', extends to near 100 the top of the sills, as shown in Fig. 3, and the lower side thereof extends to near the 105 top of the sills, as shown in Fig. 3, and the lower side thereof extends to near the 110

floor a^2 , of the filler between the sills and which serves as a guide and support for the draft rigging.

Inserted within the tail strap with the rear or inner end bearing against the follower block b' , is the casing D, of malleable iron or other suitable material which, as shown, is roughly rectangular in form with reentrant angles at the corners, as shown in Figs. 3 and 5, thus reducing the widths of each of the sides of said casing to a size approximately suitable to fit between the walls afforded by the shoulders a^2 and to fill the yoke vertically of the draft gear described.

Said casing, as shown, has arranged therein a plurality of short, thin steel plates of high resiliency and arranged, as shown, in five groups, the inner d , consisting as shown, of eleven plates, the next adjacent group d' , consisting of ten plates, and the next outer d^2 , the next group d^3 and the outermost group d^4 , also consisting of eleven plates. As shown, the two outermost groups are separated from each other by a spacing block d^5 , having concaved and inwardly tapered sides and connected at their inner thin edges. Said spacing blocks d^5 , are connected centrally by means of a thin web or plate d^6 .

The groups d^3-d^2 are separated by an oval spacing block d^7 , against which said groups bear at their center from which point said oval spacing block tapers convexly toward the ends, which extend closely to the sides of the casing D. Between the groups d^2-d^1 is interposed spacing blocks d^8 , identical in construction with the spacing block d^5 , before described, and also connected by a web blade d^9 . The groups $d-d'$, are separated by a full oval spacing block d^{10} , identical in construction with the oval spacing block d^7 , and similarly disposed and as shown, the ends of said inner groups of springs d , bear against the inclined inner portion of the casing, which is concaved to afford a distance between the center of the last plate of said group and the inner end of the casing equal to the distance between the spacing web d^6 or d^9 , and the adjacent spring plate.

The abutment block E, is shaped transversely to fit in the end of the spring casing D, and as shown in Figs. 2 and 4, is convex on its inner end having the same convexity as one side of one of the full ovals and bears at the center of the outer group of plates. As shown also, said abutment is provided at its inner end with an upper and a lower flange $e-e'$, which fit into the space in said casing above and below the springs and extends inwardly for some distance to insure said abutment telescoping into said casing under buffing stress or pulling stress and preventing at all times the displacement of the abutment from position. The forward

end of the abutment is square, as shown, with the side walls thereof bearing firmly against the forward follower block b .

The operation is as follows: The casing D, with the springs inserted therein in groups in the order shown in Figs. 1 and 2, with the spacing blocks in place, the full ovals being arranged alternately between the concave end blocks, so that said groups of springs are engaged by said spacing blocks alternately at the ends or the middle, as shown, the abutment block bearing against the middle of the first group of springs and the inner group bearing at its ends against the inclined end walls of the casing. When buffing stress is applied, the tail of the draw-bar being in positive bearing against the follower block b , the buffing stress is delivered centrally upon the first group of springs tending to flex the same more or less and inasmuch as said springs are flat and of equal area, and in positive bearing for their entire surface one upon another, it follows that even a very slight relative movement of the plates in a group must of necessity produce very great surface friction, the frictional surface in each group in that case being obviously the sum of the areas of the number of plates less one, inasmuch as the outer surfaces of the outermost plates of each group are not in frictional engagement. Inasmuch as the outermost group contacts only at the ends as does the next adjacent group d^3 , which group bears at its middle on the oval d^7 , and the group d^2 , again at its middle and ends, or, in other words, inasmuch as the groups are in bearing alternately at their ends and at their middle, it follows that sudden inward stress due to buffing is transmitted to the entire number of groups, the outermost groups, however, receiving the first impulse to a slight extent and must sustain the greater stress. Owing to the construction of the alternate arrangement of the movable full oval spacing blocks and the inwardly tapering backs, it is obvious that the distance between the contact faces on the spacing blocks decrease as compression increases and furthermore that whatever the buffing stress, practically the entire force thereof is absorbed by the surface friction between the plates as well as by the resiliency and having driven the plates inwardly to full or less than full compression, the friction between the plates tends to prevent recoil by absorbing such stress frictionally, that is to say, there being some pressure maintained upon the draft gear at all times, and whatever the resiliency of the spring plates the frictional pressure of the plates one upon another must be overcome before appreciable recoil can take place, and such frictional pressure, although very slightly, when considered in relation to the entire fric-

tional area of the plates is amply sufficient to account for the absence of recoil. The stresses exerted in pulling are absorbed in much the same manner. The draft of the 5 tail strap on the follower block b' , forces the spring casing with its contents forwardly upon the abutment E, which, of course, is held from movement on the follower block b , which is in full bearing upon 10 the stationary abutments B. In consequence, all the springs in each group are flexed slightly, the amount being of course, dependent in part upon the stress and upon the number and thickness of the plates and 15 the number of groups.

In practice, it has been found that no appreciable attrition or surface wearing of the plates occur for the reason that the frictional surface being enormously great 20 owing to the large number of plates and the larger surface of each exposed it follows that even with the enormous stress due to buffing, the actual frictional pressure applied on each plate per square inch is relatively small although the frictional effect 25 produced is sufficient to confine the travel in the draft gear to very small limits. The ordinary stresses produced in such a draft gear when the train is in motion produces 30 exceedingly slight movement in the plates relatively each other and in consequence, the grind and wearing effect heretofore present in friction draft gears is absent inasmuch as in lieu of the very small friction surface 35 provided in standard friction draft gears, the actual frictional surface utilized is enormously great and this friction surface may be increased by increasing the number of plates or the number of groups of plates or 40 both.

Although I have heretofore used spring plates approximately one fourth inch in thickness, I have found in practice that excellent results are attained by the use of 45 such spring plates approximately one eighth of an inch in thickness, thus enabling the greater number of plates to be used in a given space and proportionately increasing the frictional absorptive power of the gear.

50 Of course, I am aware that the casing may assume other forms than that illustrated and described, and if desired, other features in the invention may be varied. I therefore do not purpose limiting this application for patent otherwise than necessitated by the prior art, as numerous details of construction and application may be va-

ried without departing from the principles of this invention.

I claim as my invention:

1. In a draft rigging the combination with the draw bar yoke and follower blocks inserted therethrough to bear respectively against the front and rear stops, of a spring casing slidably supported in said yoke and bearing at one end against one of the follower blocks, an abutment block bearing against the other follower block and extending into the casing, a plurality of groups of flat, thin spring plates arranged within the 65 spring casing, each group movably supported in the casing and the groups separated alternately at the middle and ends and guide flanges integral with the abutment block and extending into the casing on opposite 70 sides of the spring groups.

2. In a draft rigging the combination with a draw bar yoke of a chamber, having a central longitudinal channel in the lower wall to receive the yoke therein, a much 80 smaller spring casing constructed to provide a guide portion to fit in the channel and shoulders to rest on the lower wall, spring friction plates arranged in groups in the casing, concave and convex bearing blocks 85 separating the groups of spring plates alternately at their ends and their middles and an abutment block fitted in one end of the small spring casing and guide flanges thereon extending into said casing on each 90 side of the spring groups.

3. In a device of the class described a casing having reentrant angles at the corners thereof providing internal and external guides, spring plates adapted to fit in the 95 casing and an abutment block adapted to fit in the end of the casing.

4. In a device of the class described a casing having an integral end wall curved on its inner side, spring plates therein, concave 100 and convex spacing members dividing the springs into groups, a bearing block curved on one end adapted to fit in the casing and guide members integral therewith extending into the casing on each side of the spring 105 groups.

In testimony whereof I have hereunto subscribed my name in the presence of two subscribing witnesses.

JAMES MILTON WAUGH.
